[57] CLAIM

The ornamental design for a hair crimping head, as shown and described.

DESCRIPTION

FIG. 1 is a top left front perspective view of a hair crimping head showing our new design;

FIG. 2 is a top plan view thereof;

FIG. 3 is a left side elevational view thereof;

FIG. 4 is a rear elevational view thereof;

FIG. 5 is a right side elevational view thereof;

FIG. 6 is a bottom plan view thereof;

FIG. 7 is a front elevational view thereof; and

FIG. 8 is a front elevational view thereof, with the hair crimping heads in an alternate position from that shown in FIGS. 1 and 7.
